CLAIM

The ornamental design for a bottle lid, as shown and described.

DESCRIPTION

FIG. 1 is a left front perspective view of a bottle lid embodying our new design, the bottle shown in broken lines for illustrative purposes only;

FIG. 2 is a left front perspective view thereof, the spout in a closed position;

FIG. 3 is a right rear perspective view thereof;

FIG. 4 is a top plan view thereof;

FIG. 5 is a front elevational view thereof;

FIG. 6 is a bottom plan view thereof;

FIG. 7 is a rear elevational view thereof; and,

FIG. 8 is a left front perspective view of a second embodiment of FIG. 1, the difference residing in the plain side walls.

FIG. 1

FIG. 2

FIG. 3

FIG. 4

FIG. 5

FIG. 6

FIG. 7

FIG. 8
